LIVE LOAD WEIGHT INDICATOR ASSEMBLY

Robert R. Crookston, Houston, Tex., assignor, by
mesne assignments, to Standard Oil Develop-
ment Company, Elizabeth, N. J., a corporation
of Delaware

Application April 9, 1952, Serial No. 281,429

4 Claims. (Cl. 254—173)

1

This application is directed to a live load weight indicator particularly adapted to be attached to the live line of an oil well drilling rig and to an assembly including the weight indicator and mounting means which enables it to be readily applied to and released from the live line.

An object of the invention is to provide a weight indicator with a clamping assembly which may be readily applied to and removed from the live line.

Another object of the present invention is to provide a clamp assembly for a live line weight indicator which automatically maintains the portion of the line passing between contact members of the clamp in a kink, bend or bight which makes a predetermined angle with the adjacent portion of the wire line even though the weight supported by the line fluctuates.

A further object of the present invention is to provide a mounting means which readily enables a clamp for the line to be readily positioned preparatory to putting it on the live line and for readily removing it from the vicinity of the line when it is disengaged therefrom.

Other objects and advantages of the present invention may be seen from the following description taken with the drawing in which

Fig. 1 is an isometric view showing an assembly embodying the present invention with the clamping portion engaged with a wire line and the mounting means mounted on the head board of a draw works;

Fig. 2 is an elevation partly in section showing details of construction of clamping assembly of Fig. 1;

Fig. 3 shows a view partly in section of the clamp assembly shown in Figs. 1 and 2; and,

Fig. 4 is a schematic view showing the air flow lines connected to the several parts of the assembly shown in Fig. 1 and thus illustrates one method of connecting the device to apparatus for automatically controlling the brakes of a drilling rig.

The present invention will now be described in greater detail in conjunction with the drawing.

Turning now specifically to Fig. 1 an embodiment of the clamp assembly is shown engaged with the line reeled on the draw works of a drilling rig. The clamp assembly is designated as A and has as its principal parts or sub-assemblies a frame member B, a frame member C, a fluid motor assembly D, a valve assembly E and valve actuating assembly F. Assembly A is engaged with a live portion of line G, that is the line moves longitudinally through assembly A as it is reeled

2

on and unreeled from the draw works. The mounting means for the assembly A consists of a suspending assembly H adapted to be suspended from the drilling derrick and a positioning assembly J adapted to be mounted on the head board of the draw works K. Compressed air is supplied to the system through a suitable means such as an air compressor, not shown in the drawing, connected to air supply line L. It will be noted that in Fig. 1 only a portion of the air supply line L is shown which is shown in Fig. 4.

Member 11 serves as a pivot securing the upper ends of frame members B and C together. Member 11 also serves as an axle upon which grooved follower wheel 12 is mounted. Another axle member 13 is secured to the lower end of frame member B and serves as the mounting means for grooved follower wheel 14. Another axle member 15 is secured to frame member C and serves as the mounting means for grooved follower wheel 16. It will be understood that the several axles will be provided with suitable bearings to allow free angular movement between frame members B and C and free rotation of the grooved follower wheels 12, 14, and 16 but since bearing assemblies are well known to the art they have not been shown in the drawing.

It will be seen that live line G is threaded between the grooved follower wheels with one side of the line in contact with grooved follower wheels 12 and 14 and the other side of the line in contact with grooved follower wheel 16. The grooved follower wheel 16 is positioned between grooved follower wheels 12 and 14 and when force is exerted through assembly D the grooved follower wheel 16 forces the line to form a kink, bend or bight between the spaced grooved follower wheels 12 and 14.

The power means for moving the frame members B and C whereby the grooved follower wheels 12, 14 and 16 are engaged with the line or whereby they may be disengaged and released from the line is the fluid motor assembly D. Fluid motor assemblies are well known to the art and it will be understood that any suitable assembly may be used. However, details of a specific embodiment are shown in Fig. 2.

Assembly D consists of a body or casing 20 whose interior is hollow and is of a generally cylindrical shape. Body 20 is secured to frame member C by cap screws 21. A piston rod 22, as seen in Fig. 2, has its left end terminating in a head 23 which is within body 20. The right end of piston rod 22 terminates in a yoke 24 which is pivotally secured to body member B by an axle

3

25. A spring 26 within body 20 encircles piston rod 22 with one end in contact with a piston rod and the other end in contact with the frame member thereby biasing piston rod head 23 to the left. When a power fluid is not supplied to the assembly D, spring 26 exerts a bias to pull grooved follower wheel 14 away from grooved follower wheel 16 thereby releasing the assembly A from wire line G.

As seen in Fig. 2, the left end of body 20 is 10 formed into a chamber 27 by means of diaphragm 28. The outer edge of diaphragm 28 is secured to chamber 20 in a fluid-tight manner by means of ring member 29 secured to body 20 by cap screws 30. The inside edge of diaphragm 28 is 15 clamped in an air-tight manner to piston rod head 23 by being bolted between retaining members 31 and 32 which members are fastened together and to the piston rod head by bolts 33. The left end of body 20 has an opening 34 to which is secured a fitting 35 for the inlet and outlet of compressed air into chamber 27. It will be seen that the admission of compressed air to chamber 27 has the effect of forcing piston head 23 to the right thereby tending to move grooved follower wheel 16 to 25 the left and grooved follower wheels 12 and 14 to the right and putting a kink or bight in live line G. In order to achieve this effect the power fluid in chamber 27 must of course overcome the bias exerted by spring 26 in addition to the tension in line G.

In the assembly of Fig. 2 compressed air is brought in from air supply line L through line 40 which is connected to fitting 41 of valve assembly E. The air, after passing through the valve, leaves through fitting 42 and passes through line 43 to fitting 35 whence it may enter chamber 27. Line 43 is connected to compressed air supply line L by means of line 106 controlled by manually operated bleeder valve 104. In normal operation of the device of the present invention when indicating the weight supported by live line G, the air may be released from chamber 27 through fitting 35, line 43 and valve E which bleeds it to the atmosphere. When an operator wishes to release assembly A from live line G this may be done by bleeding air from chamber 27 through bleeder valve 104.

The valve actuating assembly F consists of an elongated member 50 which is pivoted to frame member B by means of a pivot 51 which is secured to the frame member and which passes through a suitable opening in member F. The upper end of member 50 is formed in the shape of a boss 52 for engagement with the end of spring 53, said spring fitting in a spring receiving recess 49 of frame member B. Thus, spring 53 exerts a bias on the upper end 52 of member 50 in a clockwise direction about pivot 51 as seen in Fig. 2. A shoe 54 for contacting with live line G is secured to member 50 at a point between its upper end and pivot 51. When fluid motor assembly D exerts a force moving grooved follower wheel 16 to the left and grooved follower wheel 14 to the right, contact of the live line G with shoe 54 has the effect of overcoming the bias exerted by spring 53 and causing member 50 to pivot in counter-clockwise direction about pivot 51. An adjustable stop member 55 is secured to frame member B and is arranged to contact member 50 between pivot 51 and the lower end of member 50 thereby limiting the movement of member 50 in the clockwise direction around pivot 51. Such a limit in the movement of member 50 is necessary when the device is released from the live line G. The

4

lower end of member 50 is secured by pin 56 to actuating member 57 of valve assembly E.

The details of valve assembly E are shown in Fig. 3. Valve body 60 has a central chamber 61 having in its side wall an inlet port 62 to which is attached fitting 41 and a delivery port 63 to which is attached fitting 42. The right end of valve body 60 has an end passage 64 in which member 57 fits slidingly and sealed by means of a sealing ring 65. The left end is provided with an adjusting screw 66.

Member 57 has its right end pivoted to valve operating member 50 as heretofore described. A central passage 67 extends from the left end of member 57 to side outlet ports 68, said outlet ports being always to the right of sealing ring 65. The left end of member 57 is in the shape of an annular valve seat 69.

Within valve body 60 is an assembly Q consisting of a body 70 having a cavity 71 with inlet ports 72 discharging thereto and having communicating therewith an axially extending passage 73. Passage 73 communicates with side ports 74 whereby fluid may be discharged there-through. Valve body 70 has a valve seat 75 where cavity 71 joins passage 73. O-rings 76 and 77 are arranged on the outside of body 70 and seal the space between bodies 60 and 70 around the inlet port 62 of valve body 60. A dumbbell shaped valve member 78 is carried by valve body 70. The central portion of valve member 78 moves slidably in passage 73, the left end thereof being adapted to seat on valve seat 75 and the right end thereof being adapted to seat on valve seat 68 of member 57. A spring 79 is arranged within body 70 and biases valve member 78 to the right. It will be seen that when member 57 is moved to the right to bring seat 69 out of contact with valve member 78 that air can bleed to the atmosphere from cavity 61 of valve body 60 (and from the delivery port 63) by means of central passage 67 and outlet ports 68 of member 57. As member 57 is moved to the left it first brings seat 69 in contact with the right end of valve member 78. At this position, with the left end of member 78 remaining seated on its seat 75, the valve is sealed off so that it does not bleed air from delivery port 63 nor does it allow air to enter through inlet port 62. Upon further movement of member 57 to the left, valve member 78 is moved to the left out of contact with its seat 75 and in this position air can pass from inlet port 62 through port 72, cavity 71, passage 73, outlet port 74 and to delivery port 63. It will be evident to a workman skilled in the art that the valve assembly E, as actuated by valve actuating assembly F, alters the amount of compressed air supply to fluid motor assembly D as a function of the position of shoe 54 which in turn is actuated by wire line G. Thus, valve E is operable to keep the kink or bend in live line G between grooved follower wheels 12 and 14 at a predetermined angle or amount.

The means J for moving the assembly A to allow it to be brought into contact or out of contact with the live line G consists of a piston and cylinder assembly. Since piston and cylinder assemblies are well known to the art, the details of construction are not shown, the showing being limited to the exterior of the cylinder 80 with a piston rod 81 projecting therefrom. The left end of cylinder 80 is provided with inlet line 82 and the right end is provided with inlet line 83. The cylinder 80 with piston 81 is

mounted on the head board of draw works K of a rotary drilling rig and is arranged for producing horizontal motion of piston rod 81. A horizontally extending rod 84 is also mounted on the head board K of the rotary in a horizontal position and serves as a rail member for a second piston and cylinder assembly. The second piston and cylinder assembly has a cylinder 85 with its end in the form of a journal or bearing 86 which slidely embraces rod 84. Projecting from the end of cylinder 85 is piston rod 85'. The end of cylinder 85 is secured to piston rod 81 by projection 87. The end of piston rod 85' which projects from cylinder 85 is pivotally connected to the lower end of frame member B by a pivot 88. Cylinder 85 is provided with air inlet lines 89 and 90.

The control means for moving pistons 81 and 85' of assembly J are shown in Fig. 4. Compressed air supply line L is shown connected to assemblies E and J. In addition a gauge M and amplifying assembly N are shown operatively connected with the assemblies E and D and also operatively connected with a fluid motor assembly O and a valve assembly P. It will be understood that valve assembly P may be operatively connected to a system for controlling the brakes of a drilling rig and may correspond for example with a like valve shown in my copending application Serial No. 198,189, filed November 29, 1950, now Patent No. 2,638,319.

Air line 91 connected to main air supply line L is connected to a valve assembly R which is shown schematically as consisting of the four branch lines 82, 83, 89 and 90, each of the branch lines being provided with a bleeder type valve designated as 94, 95, 96, and 97, respectively. It will be obvious that by suitable manipulation of the valves 94, 95, 96, and 97 that the piston rod 86 and hence the assembly A can be moved horizontally either back and forth or in and out with respect to head board K. The assembly A is preferably suspended from the assembly H consisting of a rail 101 which is adapted to be fastened horizontally to the drilling derrick (not shown in the drawing). Mounted for movement on rail 101 is a carriage 102 to which is attached a line 103 terminating at its lower end in a clevis 104 which is fastened to the upper end of clamp member B by means of a pin 104'. Thus, when the lower end of the assembly A is moved by assembly J, the upper end moves freely in a line parallel to the axis of piston rod 81 and mounting rod 84.

If the assembly A is engaged with the live line G, it is desired to release it therefrom. This may be done by bleeding off air through the outlet of bleeder valve 105 arranged in the air line 106 which line connects air supply line L with air line 43 between fitting 35 and assembly E. When air is bled from the chamber 27, the spring 26 takes command causing grooved follower wheels 14 and 12 to move to the left and grooved follower wheel 16 to move to the right with respect to each other so that the follower wheels become clear of wire line G. It is noted that as soon as shoe 54 moves out of contact with live line G, valve assembly E seals off the inlet port 62 so that no more air can pass through valve E to power unit D. When the grooved follower wheels 12, 14 and 16 have been disengaged from live line G, the assembly may be moved by manipulating piston rods 81 and 85' until it is away from the immediate vicinity of wire line G and thus leaves it unobstructed by 75

the assembly. If the assembly is disengaged from wire line G, the steps engaging it involve first moving it by means of assembly J until the grooves of the grooved follower wheels 12, 14, and 16 are in line with the axis of wire line G whereupon valve 95 may be momentarily opened to supply compressed air to power means J, which in turn moves the two frame members B and C and brings the grooved follower wheels 12, 14, and 16 and shoe 54 into contact with live line G. When shoe 54 comes into contact with live line G, the actuating assembly F and valve assembly E take command and cause the assembly to maintain a bend or kink of a predetermined amount in the live line G.

As shown in Fig. 4, the power assembly D and valve E are operatively connected to a control system. This control system, for example, may be an automatic control for a drilling rig 20 of the type disclosed in U. S. Patents 1,837,439, Brantley, November 10, 1931, 2,133,016, Brantley, October 11, 1938, and 2,489,449 Crookston, November 29, 1949.

As shown in Fig. 4, fitting 35 of power assembly D is connected through line 110 to one side of gauge M. It is also connected through line 110 and branch line 111 to the pressure amplifier N.

Pressure amplifier assembly N is described and 30 claimed in copending application Serial No. 242,302, filed August 17, 1951, in the name of Arthur J. Seljos. However, in order to describe more fully the operation of the live load weight indicator assembly of the present application, 35 the details of construction of pressure amplifier N will be given.

Pressure amplifier N consists of body 112 having a chamber 113 and a chamber 114 on opposite sides of diaphragm assembly 115. An inlet port 116 discharges into chamber 114 and is connected with line 110 through branch line 111. An inlet 117 discharges into chamber 113 and is connected through branched line 118 to gauge M and to regulator valve 119 which allows air at a constant pressure to pass from main air supply line L to branched line 118 and thence to gauge M and also to chamber 113.

Body 112 also has a chamber 120 with an inlet port 121 and delivery port 122 connected thereto. Within chamber 120 is an assembly Q' which is identical with valve assembly Q of the valve assembly E so will not be again described. A valve actuating member 123 for actuating member 78 of assembly Q' is mounted in the center portion of diaphragm 124 which has its outer edge secured to housing 112 and the space adjacent the left side of the diaphragm in fluid communication with chamber 120 and the space adjacent the right side in contact with the atmosphere through port 125 extending through the wall of housing 112. Actuator 123 has a discharge passage 126 and surrounding the left entrance of the passage is a seat 127 which cooperates with the right end of valve member 78. A rod 128 sealed by O-ring 129 passes through the wall of housing 112 and has its right end in contact with diaphragm assembly 115 and its left end in contact with member 123. A spring 130 is arranged in chamber 120 to bias member 123 to the right. Side port 122 is connected to a fluid motor O (which may be a piston and cylinder or diaphragm assembly) by line 131. Port 121 is connected to air supply line L.

In effect, assembly N balances the pressure in

the fluid power unit D against a constant predetermined pressure coming through pressure control valve 119, these two pressures acting as a control means to allow air from air supply line L to pass through assembly Q' to delivery port 122 and thence to fluid motor assembly O. That is, if the pressure in assembly D and thus the pressure in chamber 114 diminishes the diaphragm assembly 115 moves to the left transmitting the motion through members 128 and 123. The first effect of this motion is to cause valve member 78 to seat on seat 127 sealing off the outlet and additional movement moves valve 78 off its seat 75 in assembly Q' allowing air to flow from air supply inlet 121 to delivery port 122. Movement of diaphragm assembly to the right first allows valve 78 to seat on its seat 75 thus preventing delivery of further air through port 122 and additional movement of diaphragm assembly 115 causes seat 127 to move away from valve member 78 thus bleeding air from the delivery port (and hence from fluid motor O) to the atmosphere.

As heretofore explained, the piston and cylinder assembly O and the valve assembly P may be 25 suitably connected to automatic control means for actuating brakes. Hence the details of construction of these devices are not here described in detail.

Having fully described and illustrated the preferred embodiment of the present invention, what I desire to claim is:

1. A clamp for a live line weight indicator comprising a first and second part pivoted together, first and second guide means on the first part, and a third guide means on the second part said guide means cooperating to engage with a wire line and bend it in a bight, a fluid operated power means mechanically connected with said first and second parts for forcing said guide means in contact with said wire line to bend said bight into a predetermined angle, a valve mounted on said assembly in fluid communication with said fluid operated power means, a contact member mechanically connected to the valve element of said valve whereby changes in the angle of the bight of said wire line change the position of said valve element in said valve.

2. A clamp for a wire line consisting of a first frame member and a second frame member pivoted to said first frame member, a pair of pulleys mounted on the first frame member, a pulley mounted on the second frame member said pulleys cooperating to engage with a wire line to force it into a bight with a predetermined angle, a piston and cylinder power assembly operatively connecting the two frame members for changing

5 the position of said three pulleys thereby altering the angle of the bight engaged by said pulleys, a valve member, means fluidly connecting the outlet of said valve with said piston and said cylinder assembly for supplying power thereto, a contact member mechanically connected to said valve member for changing the position of said valve member as a function of the relative changes in the position of said two frame members.

15 3. A live line weight indicator assembly clamp comprising a first piston and cylinder assembly adapted to be mounted on the head board of a draw works with its axis parallel to the axis of the draw works reel, a track adapted to be mounted on the head board of the draw works parallel with the piston rod of said first piston assembly, a second piston and cylinder assembly journaled on said track for slidable movement thereon and mechanically connected to the first piston and cylinder assembly to be moved thereby along said track, a suspending means adapted to be suspended from the drilling derrick, a clamp consisting of a first part and second part pivoted together and suspended from said suspending means, first and second guide means on the first part of the clamp and a third guide means on the second part of the clamp, said guide means cooperating to engage with the live line of said draw works and to bend it in a bight, a fluid operated power means mechanically connected with said first and second parts of the clamp for forcing said guide means in contact with said wire line to bend said bight into a predetermined angle, a valve mounted on said assembly in fluid communication with said fluid operated power means and a contact member mechanically connected to the valve element of said valve whereby changes in the angle of the bight of said wire line change the position of said valve element in said valve.

4. A device in accordance with claim 3 in which said suspending means consists of a rail adapted to be mounted horizontally in the drilling derrick with a carriage slidably mounted on the rail and with a cable having one end secured to the carriage and the other end secured to said clamp.

ROBERT R. CROOKSTON.
